CLAIM

I claim the ornamental design for laser tag chest plate, as shown and described.

DESCRIPTION

FIG. 1 is a front perspective view of a laser tag chest plate showing my new design.

FIG. 2 is a rear perspective view of the laser tag chest plate.

FIG. 3 is a front view of the laser tag chest plate of FIG. 1.

FIG. 4 is a rear view of the laser tag chest plate of FIG. 1.

FIG. 5 is a right side view of the laser tag chest plate of FIG. 1.

FIG. 6 is a left side view of the laser tag chest plate of FIG. 1.

FIG. 7 is a top view of the laser tag chest plate of FIG. 1; and,

FIG. 8 is a bottom view of the laser tag chest plate of FIG. 1.

The broken lines shown in the drawings depict portions of the laser tag chest plate that form no part of the claimed design.

1 Claim, 6 Drawing Sheets
